N° 614

Augur, Richmond & Smith's Cylinder Coal Stove Design

Patented Dec 20th 1853

James Wager, Volney Richmond, & Harvey Smith,

of Troy N. Y.

Letters Patent No. 614. Dated Dec. 20th, 1853.

The schedule referred to in these Letters Patent, and making part of the same:

To all whom it may concern:

Be it known that we, James Wager, Volney Richmond, & Harvey Smith of the City of Troy and County of Rensselaer, in the State of New York, have invented or produced a new and original design for a cylinder Coal stove, which we call the "Orient," and we do hereby declare that the following is a full, clear, and exact description of the same reference being had to the accompanying making a part of this specification, in which Fig. 1 is a perspective view of the stove.

The description of our design for the Orient Cylinder Coal stove is as follows: viz: A is the top rim, a section of which shows ogee cove and ovolu mouldings separated by fillets (a) and the general outline of which is an octagon. B is the dom with double Gothic arch (b) supported by three columns (ccc) the tops of which are finished with cove ogee and bead mouldings (d), the hexagon bases (ccc) of which are finished with bead & cove mouldings (fff). The main arch is formed by a cluster of three beads (g). C is a panel making one side of the octagon top, and which is decorated with two columns (h) & are supported by corbels (i). These columns support a double arch (jj) & from which hangs down a pendant (k) between the columns. D is an octagonal plate on the top of the main body of the stove ornamented around the edge with semicircular scallops (l) & bordered around also with ball flower ornaments (m) and above which is a heavy ogee moulding (n). E is one of the 8 octagon open work panels surrounding the fire pot or cylinder. These perforated panels are decorated with a combination of scrolls (o) & also with a variety of leaf ornaments (p). F is the square plate forming the top of the base. Around the edge of this plate are concave scallops (q) & also around which at equal distances are scroll shell ornaments (s) placed upon the heavy ogee moulding (r). Each corner of this plate has on it a spandrel panel (t) surrounded with cove & bead mouldings (u) and in the center of which is a circular cove or bead ornament (v). G is the side of the base which has in the middle a shell ornament (w) & each end of this plate is decorated with scroll & leaf ornaments (x). H is the bottom plate of the stove. The hearth or front of this plate has a combination of scroll & leaf ornaments (y & z) & the sides also have a combination of the same decorations (x) separated in the center by a shell ornament (y). I is the leg of the stove. This has three flutes (xx) lengthwise & the top of these flutes have each a projecting egg ornament (m). The foot of the leg has a scroll ^{shell} ornament (s) the ends of the scroll being connected by a bead chain (s).

Having thus fully described our design for Orient cylinder Coal stove, what we claim as new, & desire to secure by Letters Patent, is the design & configuration of the plates, as herein described, and represented in the accompanying drawings.
